SPACE DISCHARGE DEVICE

Hyman Olken, Washington, D. C.

Original application May 19, 1943, Serial No. 487,563. Divided and this application March 15, 1945, Serial No. 582,961

2 Claims. (Cl. 315—21)

(Granted under the act of March 3, 1883, as amended April 30, 1928; 370 O. G. 757)

1

This invention relates to structure of electron discharge devices and is a divisional application of my copending application, Serial No. 487,563, filed May 19, 1943, and issued May 29, 1945, as Patent No. 2,376,882.

The principal object of this invention is to provide a novel and improved structural arrangement for an electron discharge device having a novel divided anode component and in which electron flow from the cathode to each of the anode portions is varied simultaneously by means of a charged, movable element positioned exteriorly of the envelope for the device. Electron flow in one of the anode-cathode circuits is thus increased simultaneously with a decrease in electron flow in the other circuit.

The electron discharge device constituting the subject matter of this invention can be used for various applications in which a change in current in response to variation in a condition is desired. The particular application illustrated is for motor control in which it is desired to control the direction of the rotation of the motor in accordance with a change in a condition such as a change in the position of a sensitive instrument pointer. However, other applications of the invention will be apparent to those skilled in the art, and the claims are to be so construed.

Referring now to the drawing, the single figure of which illustrates a preferred embodiment of the invention, there is shown at 10 an envelope which has an arcuately shaped portion 10a at the top. Within the envelope and near the bottom is a cathode 11. At the top end of the envelope near the arcuately shaped portion are a pair of screen electrodes 12a and 12b accelerating electron flow in the device. These screens should have substantially the same arcuate contour as the envelope portion 10a. Suitable potential for these electrodes is obtained from any convenient source, such as battery 13. The negative terminal of this battery is connected to the cathode 11 and the positive terminal is connected to both of the accelerating electrodes 12a and 12b.

Between the electrodes 12a and 12b and the interior wall of the arcuately shaped envelope portion 10a are two more screen electrodes 14a and 14b. The wires constituting the screen electrodes 12a and 14a are aligned with respect to cathode 11 and the wires of screen electrodes 12b and 14b are similarly aligned.

Screen electrodes 14a and 14b may be termed the anode elements of the discharge device. Electrode 14a is connected via conductor 15 to one field winding 16 of a motor 17 and through the

motor armature 18 to an intermediate point 13a of the battery 13. The other electrode 14b is connected via conductor 19 to another field winding 20 of motor 17 and thence also through motor armature 18 to the battery point 13a.

Positioned outside of the envelope adjacent the arcuate portion 10a is a plate 21 having the same contour as envelope portion 10a. This plate is supported by an arm 22 the lower end of which is mounted on a shaft 23. The latter may comprise the shaft which carries the pointer element 24 of any instrument. Plate 21 is charged to a negative potential with respect to the cathode element 11 by means of a battery 25 connected thereto by conductor 26.

By adjusting the voltage on the screen electrodes 12a and 12b, the streams of electrons coming through the interstices in these screens can be focussed to be in a straight or even in a divergent beam as they pass through the interstices in electrode screens 14a and 14b. The relative spacings and voltages on screens 12a, 12b and 14a, 14b are furthermore so chosen that the accelerated electrons go through the interstices in screens 14a and 14b but only slightly beyond and then turn back. The streaming electrons being slowed up near screens 14a and 14b, a substantial portion of them will be absorbed by screens 12a and 12b, respectively.

30 The operation of the device should now be apparent. With the negatively charged plate 21 in a center position, the position shown in the drawing, electron flow from cathode 11 will be divided into two streams of equal magnitude. Under this condition, electron flow between cathode 11 and anode screen 14a will be the same as that between cathode 11 and anode screen 14b, with the result that the motor field windings 16 and 20 will be equally energized producing magnetic fields of equal strength. However with the field connections as shown in the drawing, it will be seen that current flow through the two motor fields are in opposite directions with respect to each other. Thus the two magnetic fields produced are likewise opposed and the resultant field is zero. Under this condition, motor armature 18 will not rotate.

50 In the event that the instrument pointer 24 and hence shaft 23 should rotate in a clockwise direction, plate member 21 will also move clockwise and cover more of screen 14b than 14a. Because of the negative charge on plate 21, electron flow to the parts of the screens 14a and 14b beneath plate 21 are retarded and reverse before reaching them. Hence, as plate 21 now covers

more of screen 14b than 14a, electron flow from the cathode 11 to screen 14b will be less than that to electrode 14a. Thus current flow through motor field winding 16 is increased while current flow through motor field winding 20 is simultaneously decreased. The difference in current flow through these two field windings sets up a resultant field in one direction proportional to the current difference and thus causes the armature 18 of motor 17 to rotate in one direction.

In the event that the instrument pointer 24 moves in a counter clockwise direction, plate member 21 moves in the same direction and covers more of screen 14a than it does screen 14b. This brings about an opposite effect with the current increasing in motor field winding 20 and simultaneously decreasing in motor field winding 16. The resultant magnetic field produced by the two field windings is then in an opposite direction and the armature 18 of motor 17 is caused to rotate in the other direction.

In conclusion, while I have illustrated a preferred embodiment of the invention, it will be understood that various changes in the construction and arrangement of parts may occur to and be made by those skilled in the art without departing from the spirit and scope of the invention as defined in the claims.

The invention described herein may be manufactured and used by or for the Government of the United States of America for governmental purposes without the payment of any royalties thereon or therefor.

What is claimed is:

1. An electron discharge device comprising an envelope, a cathode disposed at one end of said envelope for emitting electrons, a pair of screen anodes disposed at the other end of said envelope, an anode-cathode circuit for each of said anodes,

- an accelerating electrode screen disposed between said cathode and each of said anodes, a negatively charged plate member disposed exteriorly of said envelope, and means for mounting said plate member for movement in overlapping arrangement relative to said anodes so that the overlap between said plate member and one of said anodes is increased while the overlap between said plate member and the other of said anodes is simultaneously decreased thereby increasing the current flow in one of said anode-cathode circuits and simultaneously decreasing the current flow in the other of said anode-cathode circuits.
- 5 2. An electron discharge device comprising an envelope, said envelope having an arcuate portion at one end thereof, a cathode within said envelope at the opposite end from the arcuate portion, a pair of arcuate screen anodes disposed within said envelope adjacent the said arcuate envelope portion, an anode-cathode circuit for each of said anodes, a positively charged arcuate accelerating screen electrode disposed between said cathode and each of said anodes, a negatively charged plate member disposed exteriorly of said envelope adjacent the arcuate portion, said plate member having substantially the same arcuate shape as said anodes and accelerating electrodes, and means mounting said plate member for movement in overlapping arrangement relative to said anodes so that the overlap between said plate member and one of said anodes is increased while the overlap between said plate member and the other of said anodes is simultaneously decreased, thereby increasing current flow in one of said anode-cathode circuits and simultaneously decreasing current flow in the other of said anode-cathode circuits.
